UNITED STATES PATENT OFFICE.

WALTER ROCKSTROH, OF POSTELWITZ, GERMANY.

DRIVING MECHANISM FOR FLAT-FORM PRINTING MACHINES.

Application filed August 31, 1927, Serial No. 216,746, and in Germany September 21, 1926.

This invention relates to flat-form or flat-bed printing presses.

In printing presses with reciprocating carriages and an intermittently driven printing cylinder either turning continually in one direction or oscillating, two kinds of driving mechanism for the carriage are used and almost exclusively known. The first kind is characterized by a crank mechanism, 5 the cross head of which is a toothed wheel which engages in a toothed bar on the under-frame and in a toothed bar on the carriage and effects the reciprocating movement of the carriage; the printing cylinder is provided in front with toothed wheels in which 10 toothed bars on the carriage engage and thereby effect the rotating movement of the printing cylinder. The second kind of driving mechanism is characterized by a separate carriage drive and by a separate printing cylinder drive and is used exclusively in the so-called two-revolution printing presses.

The object of the present invention is to simplify the construction of the driving mechanism for flat-bed printing presses to 25 substantially shorten the machine and consequently to reduce the cost of construction. Furthermore by the provision of a rib passing through the whole breadth and height 30 of the carriage track a machine of high printing capacity is produced with the use of very little material. These special features are achieved by ensuring that the periodical change in the direction of rotation of the printing cylinder actuating the carriage is brought about and effected by 35 means of coupling members that in the dead-point position of the carriage are switched from left hand turning to right hand turning and vice versa.

One embodiment of the invention is shown by way of example in the accompanying drawing in which

Fig. 1 is an elevation and

Fig. 2 is a plan view.

The actuating motor α drives a coupling b directly in one direction of rotation and a similar coupling c indirectly by means of an interposed toothed wheel d in the opposite direction. Both couplings have a common shaft e . Magnetic couplings of the usual kind are, for example, used. The switching in of the coupling at the dead point positions of the carriage is effected alternately by switches r and s , which are connected by a rod t . On reaching the front

dead-point position of the carriage k , the coupling b is disconnected, whilst at the same time the coupling c is put in action; on reaching the rear dead-point position 60 of the carriage this procedure is reversed. By means of the toothed wheels f , g , h , i , the cylinder l is driven. The toothed wheels m mounted at the ends of the printing cylinder are in engagement with toothed bars n on 65 the carriage k and impart a reciprocating movement to the carriage.

In addition to a saving in weight, this arrangement has the special advantage that the carriage track o over its whole breadth 70 and height can be stiffened by means of a rib p , which cannot be fitted in the case of the classes of driving mechanism hereinbefore referred to. A machine according to the invention has therefore greater stability 75 without any increase in material.

What I claim is:—

1. In a flat-bed printing press comprising a driven printing cylinder and a reciprocating carriage actuated therefrom, the combination with the cylinder driving mechanism of alternative coupling members, and change-over means actuated when the dead-points in the carriage travel are reached to change over the cylinder drive through said members.

2. In a flat-bed printing press comprising a driven printing cylinder and a reciprocating carriage actuated therefrom the combination with the cylinder driving mechanism of alternative coupling members in the cylinder drive, and means actuated by the carriage when it reaches the dead points in its travel to change over the drive from one coupling member to the other.

3. In a flat-bed printing press comprising a driven printing cylinder and a reciprocating carriage actuated therefrom the combination with the cylinder driving mechanism of alternative electrical coupling members in the cylinder drive, and means actuated by the carriage when it reaches its dead point positions to switch over the drive from one coupling member to the other.

4. A flat-bed printing press comprising a printing cylinder, means including a coupling member for driving said cylinder in one direction, means including a second coupling member for driving said cylinder in the opposite direction, a reciprocating carriage, means for actuating said carriage from said cylinder, and means actuated as

- said carriage reaches each of its dead point positions for rendering one coupling member ineffective and rendering the other coupling member effective.
- 5 5. A flat-bed printing press comprising a printing cylinder, means including a coupling member for driving said cylinder in one direction, means including a second coupling member for driving said cylinder in
- 10 the opposite direction, a reciprocating carriage, means for actuating said carriage from said cylinder, and means actuated by said carriage as it reaches its dead point positions for rendering the active coupling
- 15 member inactive and rendering the inactive coupling member active.
6. A flat-bed printing press comprising a printing cylinder, means including an electrical coupling member for driving said cylinder in one direction, means including a 20 second electrical coupling member for driving said cylinder in the opposite direction, a reciprocating carriage, means for actuating said carriage from said cylinder, and switches controlling said coupling members 25 and actuated by the carriage on reaching its dead point positions for changing over from one coupling member to the other in the drive to the cylinder.

In testimony whereof I have signed my name to this specification.

WALTER ROCKSTROH.
